UNITED STATES PATENT OFFICE.

CHARLES A. MILNE, OF DETROIT, MICHIGAN, ASSIGNOR TO TRUMAN PARSHALL, OF DETROIT, MICHIGAN.

MECHANICAL MOVEMENT.

1,127,065.

Specification of Letters Patent. Patented Feb. 2, 1915.

Application filed November 6, 1913. Serial No. 799,436.

To all whom it may concern:

Be it known that I, CHARLES A. MILNE, a citizen of the United States, residing at Detroit, in the county of Wayne, State 5 of Michigan, have invented certain new and useful Improvements in Mechanical Movements; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to a mechanical movement and consists in the construction and arrangement of parts hereinafter more fully set forth and pointed out particularly in the claim.

20 The object of the invention is to provide simple and efficient means for converting and transmitting rotary into reciprocating motion, the mechanism being especially adapted for use in connection with recipro-

25 cating pumps or air compressors, wherein the driving mechanism is required to be confined within a small and compact area, and in which it is desirable to actuate a multiple of reciprocal plungers from a common cen-

30 ter through the rotary movement of a driving shaft, in such manner as to afford direct contact between the driving parts so as to minimize the number of moving parts, to reduce friction and to attain a high effi-

35 ciency of the power applied.

The above object is attained by the employment of the construction and the arrangement of parts as illustrated in the accompanying drawings, in which:—

40 Figure 1 is a central longitudinal section through the mechanism as applied to an ordinary multiple cylinder air compressor the shafts and piston rods being shown in elevation. Fig. 2 is a transverse sectional view through the parts and containing case taken on dotted line 2—2 of Fig. 1. Fig. 3 is an elevation of the detached oscillatory disk for transmitting movement to the pistons.

45 50 Referring to the drawings by the characters of reference marked thereon, 1 and 2 designate the parts of the containing case or cylinder members, each of which is bored

to form a plurality of diametrically opposed cylinders 3 therein, said members at 55 their inner ends being provided with flanges 4 through which bolts 5, with nuts 6, are passed to couple said parts together, the cylinder members being so joined as to dispose the cylinders therein in axial alinement with 60 each other. The outer ends of the cylinder members 1 and 2 are closed by integral heads 7 which are surmounted by concaved heads 8 secured thereto by bolts 9 through the flanges thereof. The concaved head at 65 the end of the cylinder member 2 is secured at its center to a threaded stem 10 of the head 7 by means of a lock nut 11, while the concaved head of the cylinder member 1 is locked in contact with the end of a stem 12 70 projecting from the head of said cylinder by means of a bolt 13 threaded therein and carrying a jam nut 14 in engagement with said head. The space between said cylinder heads and concaved heads forms compression chambers which communicate with the cylinders through the ports 15.

The construction and arrangement of the cylinder members as described is common in air compressors and is not essential to the 80 operation of the mechanism shown herein for transmitting and imparting a reciprocal motion to one member through the rotary movement of another, as this mechanism is adaptable for various other uses, but is 85 shown in connection with an air compressor to better illustrate its operation.

Journalized concentrically within the central portion of the cylinder member 2 to rotate in the bearing 16 formed therein, is a 90 drive shaft 17, and mounted upon the end of said shaft, and lying concentrically within and between the cylinder members 1 and 2, is an enlarged circular head 18 having an oblique face which extends across the plane 95 of the axis of the shaft at an angle thereto, forming a cam face 19, and projecting at right-angle from said cam face concentric therewith is a hub 20, and lying concentric with and freely receiving said hub, is an annular washer or ring 21 carrying a multiple of steel balls 22 extending transversely through the body at intervals through the circumference thereof, in the form of a ball thrust bearing.

100 105 Mounted in each of the cylinders 3 is a

piston 23, and connected rigidly to each opposed pair of pistons is a piston rod 24 having an enlarged body portion or head 25 formed thereon midway the length thereof.

5 Extending centrally in said heads diametrically of said piston rods and in opposed relation to each other are cylindrical apertures 26.

Mounted in a bearing 27 formed centrally 10 in the cylinder member 1, and extending therein in axial alinement with the rotatable shaft 17, is a stub shaft 28, the inner end of which is reduced and terminates in the form of a ball 29. The opposite end of said stub 15 shaft abuts against the inner end of the bolt 13 threaded into the stem 12 at the opposite end of the shaft bearing 27, whereby, through the rotation of said bolt, said shaft may be adjusted longitudinally of its bearing, said bolt being locked against rotation by the jam nut 14 thereon.

As a means for imparting a reciprocating movement to the piston rods and their pistons through the rotary motion of the shaft 25 17, an oscillatory disk 30 is interposed between the thrust ball bearing ring of the cam face 19 and the ball 29 of the stub shaft 28. Said oscillatory disk is provided upon one side with a central concavity 31 which 30 forms a socket for the reception of the ball 29 of the shaft 28, whereby a central pivotal contact is formed between said disk and shaft. The opposite face of said disk is provided with a flat surface for engagement 35 with the balls forming a thrust bearing with the face of the cam. The periphery of the oscillatory disk is provided with integral extensions carrying balls 32 upon diametrically opposite sides thereof (see 40 Fig. 3), the diameter of said balls being sufficiently less than the diameter of the cylindrical apertures 26 of the piston rods 24 to enable said balls to lie freely within said apertures in contact with and in a manner to permit of a slight rotary as well as sliding contact with the walls thereof, as clearly shown in Figs. 1 and 2.

By this arrangement, the flat face of the oscillatory disk being held in contact with 50 the cam face of the rotary shaft through the central pivotal contact of its opposite face with the ball of the stub shaft, said disk will be caused at all times to lie in a line with the plane of the cam face of the rotary shaft, and as said shaft is rotated a rocking or oscillating movement will be imparted to said disk as the position of the cam face changes or reverses with respect to a right-angle plane with the axis about which it rotates, thus actuating said disk in sequential 55 progression throughout its circumference, and through the pivotal contact of the piston rods with the ball extensions on said disk, said piston rods will be alternately reciprocated in their opposed cylinders, as

indicated by dotted lines in Fig. 1, the air or other substance compressed by the movement of the pistons passing through the ports in the heads of the cylinders is discharged into the compression chambers. 70

It will be observed that as the disk rocks or oscillates upon its pivotal center, the face of the disk in contact with the cam face through the interposed bearing ring will be caused to travel in a direction diametrically 75 across said cam face, while at the same time said cam face is rotating about the center or axis of said disk, thus producing a surface movement in two directions between the meeting parts, and the pressure exerted 80 upon the opposed faces of the cam and disk being carried by the rolling contact of the interposed steel balls permits this double movement with but slight frictional resistance or wear upon the bearing surface, while 85 the end thrust exerted upon the cam shaft is carried by a ball thrust bearing ring 33 interposed between the forward end of the shaft bearing 10 and the shoulder of the head 18 of the cam. It will thus be seen that 90 a ball contact bearing is formed between all of the moving parts of the mechanism subjected to direct strain and wear, that such moving parts are comparatively few in number and simple in their construction, and 95 that the application of power to the rotary shaft will be directly transmitted to impart an alternating or reciprocating movement to two or more reciprocal members.

Because of the action of the cam face in 100 causing a continuous oscillation of the pivotal disk in sequential progression circumferentially thereof, a large number of pistons may be arranged about said disk and actuated simultaneously by contact with its 105 periphery to produce a continuous flow of air or other substance for use for various purposes, while the construction of the device is such as to render it practically noiseless in operation and comparatively free 110 from frictional resistance, and the arrangement of the parts being so disposed as to enable an adjustment to compensate for wear, in practically all of the contact or wearing points, to be effected through the 115 adjustment of the stub shaft from the exterior of the case by means of the adjusting bolt as before described, thus rendering accessibility to the interior of the case unnecessary for the purpose of keeping the parts 120 in close working order.

Having thus fully set forth my invention, what I claim as new, and desire to secure by Letters Patent, is:—

A mechanical movement comprising a retaining case, a revoluble shaft journaled in said case, reciprocal rods mounted in said case, each rod having an aperture formed diametrically therein, a pivotal shaft mounted in said case in axial alinement 125

with said revoluble shaft and adapted for adjustment longitudinally, a head on said revoluble shaft having a face cam thereon, an oscillatory disk pivoted centrally upon said pivot shaft and having peripheral extensions upon opposite sides thereof engaging the apertures in said reciprocal rods, a thrust bearing interposed between the face

of said oscillatory disk and the face of the cam of said revoluble shaft.

In testimony whereof, I sign this specification in the presence of two witnesses.

CHARLES A. MILNE.
